UNITED STATES PATENT OFFICE.

FREDERICK GERHARDT, OF SAN FRANCISCO, CALIFORNIA.

DIE FOR LINING BEARINGS.

Application filed October 14, 1920. Serial No. 416,866.

To all whom it may concern:

Be it known that I, FREDERICK GERHARDT, a citizen of the United States, residing at San Francisco, in the county of San Francisco and State of California, have invented new and useful Improvements in Dies for Lining Bearings, of which the following is a specification.

This invention relates to devices for lining bearings and has for its object to simplify and improve the construction and operation thereof.

The present device is especially adapted for use in lining connecting rod bearings of internal combustion engines, and comprises a stationary die and a movable die disposed on vertical axes, between which a bearing member is clamped and into which molten metal, such as Babbitt or white metal, may be poured, the die being so shaped as to cause the molten metal to set evenly around the interior of the bearing member. The device also includes means operated by the opening of the movable die to cause the bearing member to be thrust away and released from the stationary die in a way to avoid injury to the lining.

One form which my invention may assume is exemplified in the following description and illustrated in the accompanying drawings, in which—

Fig. 1 shows a plan view of a device embodying my invention,

Fig. 2 shows a front elevation of the same with the movable die member open,

Fig. 3 shows a plan view of the device with the die member closed, and

Fig. 4 shows a sectional view on the line 4—4, Fig. 3.

In the form herein shown I employ standards 10 between which is fixed a frame bar 11, such bar detachably receiving a male die 12 by means of bolts 13. This die, it will be noted, is disposed with its axis vertically and at each side thereof is a knock-out pin 14 slidably received in the frame bar. Each knock-out pin has a flange 15 near its forward end and is normally held retracted by means of a coil spring 16. These pins are spaced so that the bolt openings in the bearing member A registers therewith, whereby to properly position the bearing member upon the male die.

A swinging member 17 is mounted on the frame bar by means of a vertical hinge pin 18 and has formed near its end a female die

19 to fit against the back side of the bearing member A and clamp the latter in place against the male die. This swinging member is cut away at 20 to allow the projecting parts on the back of the bearing member, as for instance an oil dip or connecting rod to extend through.

I provide suitable means to lock the die members together, such for instance as a handle 20 having a notch 22 to cooperate with a lug 23 on the frame bar. The hinged end of the swinging member cooperates with a plunger 24 slidably mounted in the frame bar, and this plunger in turn engages with the ends of a pair of levers 25 which are fulcrumed at 26 upon the frame bar and have their opposite ends co-acting with the knock-out pins 14.

In the operation of the device the dies are opened and the bearing member is placed against the stationary die and held temporarily in place by the projecting ends of the knock-out pins 14. The swinging member is then closed and locked in place and thereafter the molten metal is poured. To admit the metal the meeting faces of the dies at the upper side are grooved, as shown at 27 in Fig. 4. The dies are so shaped as to allow the metal to fill in evenly around the interior of the bearing and form a flange 28 at each side thereof. Wherever desired the male die can be provided with ridges 29 whereby to form oil grooves in the lining.

After the metal is poured and sufficiently set the dies are unlocked and the movable members swung outwardly. Being at the extreme end of a long arm the path of movement taken by the female die is such as to permit withdrawal without any danger of disturbing the position of the bearing member. When the movable member nears the limit of its opening movement it strikes the plunger 24 and causes the knock-out pins to thrust the bearing member away from the male die.

The movement of the bearing member away from the stationary die will be equal at both sides and therefore there is no danger of the lining becoming mutilated or injured. A die as here shown is simple to construct and is easily operated. It permits a large number of bearings to be poured in a short space of time and insures that the lining will be properly and evenly formed, and wherever necessary provides for the formation of oil ducts or grooves in the lining. With a device of this char-

acter little or no scraping of the bearing is required. Different size dies are provided for different sizes of bearings.

Various changes may be employed in the construction and operation of the several parts of the device without departing from the spirit of my invention as disclosed in the appended claims.

Having thus described my invention, 10 what I claim and desire to secure by Letters Patent is—

1. A device for forming a lining and fillet in a split bearing, comprising means engageable with the bolt openings in the flanges of the bearing-half to support the same, an inner die member spaced from the ends and inner circumference of the bearing-half, an outer die member to engage the bearing-half and clamp the same in place, 20 said outer die member co-operating with the inner die member to enclose a space at each end of the bearing-half for the fillet.

2. A device for forming a lining for a connecting rod bearing comprising lugs to enter the bolt openings in the flanges of the bearing-half to support and position the latter, an inner die member around which the bearing-half fits, a swinging outer die member engageable with the exterior of the 30 bearing-half to clamp the same in place and means actuated by the withdrawal of the outer die member and engageable with said lugs to cause the lugs to thrust the bearing-half away from the inner die member.

3. A device for forming a lining and fillet in a connecting rod bearing, comprising lugs to enter the bolt holes in the flanges of the bearing-half to support and position the same, an inner die member spaced from 40 the ends and inner circumference of the bearing-half, a horizontally swinging outer die member to engage the bearing-half, and to co-operate with the inner die member to

enclose a space for the fillet, clamping means to retain the outer die member in place and means actuated by withdrawal of the outer die member and engageable with said lugs to cause the lugs to thrust the bearing-half away from the inner die member. 45

4. A device for lining connecting rod bearings, comprising a frame, lugs slidably mounted in the frame in position to enter bolt openings in the flanges of the bearing-half, an inner die member fixed to the frame and around which the bearing-half fits, an arm hinged to the frame and carrying an outer die member to co-operate with the inner member and clamp the bearing-half in place, and means actuated by outward movement of the hinged arm and in engagement 60 with said lugs to depress the lugs and thereby thrust the bearing-half away from the inner die member. 55

5. A device for use in lining bearing halves comprising a frame including a transverse bar, an inner die secured to one of the side faces of said bar, a plurality of horizontally disposed lugs slidably mounted on said bar and projecting therethrough to enter the bolt holes in the bearing half 70 to support and position the latter, a horizontally swinging outer die hinged to said bar to engage the bearing half and clamp it in position relative to the inner die, pivoted levers connected to said lugs, and a member connected with said levers and adapted to be engaged by the outer die when the latter is swung outwardly whereby the levers will be actuated to depress the lugs 75 to disengage the bearing half from the inner die. 80

6. The combination as set forth in claim 5 including means for locking the outer die in closed position.

FREDERICK GERHARDT.
